UNITED STATES PATENT OFFICE

CHARLES W. GREEN, OF ILLION, NEW YORK, ASSIGNOR TO REMINGTON ARMS COMPANY, INC., A CORPORATION OF DELAWARE

CASH REGISTER

Original application filed April 13, 1927, Serial No. 183,392. Divided and this application filed November 15, 1928. Serial No. 319,469.

This application is a division of my co-pending application, Serial Number 183,392, filed April 13, 1927, to which reference may be had for a more complete description of the cash register to which the present invention has been applied. While the improvements set forth in this application are shown in conjunction with a particular type of cash register as illustrated in the parent application their utility is by no means limited to this specific embodiment. The improvements are of such a nature that they may be applied in various modifications to many other types of cash registers and accounting machines.

This invention has for its principal object the provision of improved means for preventing the simultaneous operation of more than one key of a group; which means shall be simple in construction, efficient in operation, and capable of expeditious and inexpensive manufacture and assembly.

More specifically, it is an object of my invention to provide key stops or pendants so constructed as to be fulcrumed without the necessity of providing the usual pivot studs.

Another object is the provision of a construction whereby said key stops or pendants may be speedily assembled and attached to or detached from the machine as a unit.

With these and incidental objects in view the invention consists of certain novel features of construction and combination of parts, the essential elements of which are set forth in the appended claims and a preferred form of embodiment of which is hereinafter described with reference to the drawings which accompany and form part of this specification.

Of said drawings:

Fig. 1 is a vertical sectional view of a cash register in connection with which the present invention is illustrated.

Fig. 2 is a rear view of the machine showing the arrangement of the groups of keys and the series of key stops associated therewith; part of the structure being broken away adjacent the upper portion of certain of the key stops.

Fig. 3 is a side elevation showing the rear

portion of a key in conjunction with a key stop member.

Framework

The various parts of the mechanism of the illustrative machine are supported by a suitable framework comprising two parallel side plates 20 and 21 (Figs. 1 and 2) these plates being spaced apart by and connected to cross members so as to provide a rigid framework structure. The forward and lower portions of the plates 20 and 21 are connected by a cross member 22 (Fig. 1) said plates being connected together at their rearward portions by cross members 23 and 24 and an intermediate cross member 25. The side plates are connected to the cross members just referred to by any suitable means such as screws passing through the side plates and into the cross members. The framework just described rests upon a drawer base 26 and may be attached thereto by screws passing through the cross members 22 and 23 and into the top of the drawer base. As best shown in Fig. 1, the mechanism is enclosed by a cabinet 27 which may be made of any desired material and rests upon the drawer base. The cabinet is slotted at 28 to receive and guide the key levers in their movements and is, furthermore, apertured at its upper end to permit the viewing of the elevated indicators through suitable diaphanous material at the front and rear.

Keys, key coupler and full stroke device

The illustrative machine comprises keys 32 (Figs. 1 and 2) which are divided into groups; one group for each denominational order, such as, for example, units, dimes and dollars. Obviously, more amount keys could be provided if more groups or higher denominational orders were desired, so as to increase the capacity of the machine. A special key 31 (Fig. 2) is also provided and is designated as the "No sale" key. This key forms no part of the present invention as no controlling key stop is associated therewith, and therefore no further mention thereof is deemed necessary.

As shown in Fig. 1, the amount keys 32 are

5 pivoted upon a shaft 33, which shaft is suitably supported by the side plates 20 and 21. Said keys 32, which carry at their respective outward ends or front portions thereof suitable key cups bearing indicia designating the 10 nature of the keys, play in the vertical slots 28 which are formed in the cabinet 27. At their rear ends the keys are guided by slots 35 formed in a plate 36 secured to the cross 15 bar 25 by screws 37.

10 Extending between the side plates 20 and 21 and resting upon the rear ends of the keys is a key coupler 39. The key coupler is pivotally supported by means of plates 40 (Fig. 1) attached to the key coupler and 15 suitably apertured to receive a transverse shaft 42, which is located approximately above the aforementioned shaft 33 and is supported by the side plates 20 and 21. It 20 will be obvious that when the forward ends of the keys are depressed the key coupler 39 will be rocked clockwise so that its rearward end will enter the notches 38 of the 25 depressed keys. The purpose of such key coupler mechanism is well known in the art and need not be discussed herein.

Key stops

While the concentric edges 45 of the 30 standing portions 46 (Fig. 1) of the various keys in conjunction with the key coupler are intended to lock all unoperated keys after the initial movement of the key coupler, it is desirable to provide mechanism to prevent depression of more than one key in a bank during a single operation of the machine. For this purpose I provide a series of key 35 stops 62, the wedge-shaped lower ends of which cooperate with the rear ends of the keys 32 in the usual manner so that upon the depression of a key in a bank the end of the 40 operated key will fill the only available gap between the key stops in that group and thus lock the remaining keys. I have so constructed said stops that they may be suspended without the necessity of providing the customary pivot studs, and at the same 45 time effectively perform their intended functions; for this purpose I form the upper end of each of said stops with a reduced portion 63, terminating in a head 64. As best shown in Fig. 2, the guide plate 36, heretofore mentioned, is bent so as to form the double channel sections 65 and 66. The lower channel 50 section 65 is provided with a series of rectangular slots 67 which are somewhat wider than the width of the reduced portions 63 of the key stops. The key stops are applied to the plate 36 in such a manner that the 55 reduced portions fit within the rectangular slots 67, the head 64 of each of the key stops resting upon a ledge 651 formed by the channelling of the plate 36. After the key stops 60 are in place the plate 36 is attached to the cross bar 25 by any suitable means, such as

70 screws 37. It will thus be seen that said stops may be readily and expeditiously placed in position on the plate 36 and the resulting assembly consisting of said stops and plate attached to the machine as a unit and that likewise said stops and plate may if desired be detached as a unit from the machine by simply removing the attaching 75 screws 37. The difference between the width of each slot 67 and the reduced portion 63 of the associated key stop 62 permits a slight 80 oscillatory movement of the key stop so that the key stops function in exactly the same manner as if they were fulcrumed by means of a pin. It may be noted that either side 85 of head 64 may serve as a fulcrum for its stop member 62, thus providing for pivotal movement of said stop in either direction 90 from normal position.

While the form of mechanism herein 95 shown and described is admirably adapted to fulfill the objects primarily stated it is to be understood that this embodiment is merely 100 illustrative, since the invention is susceptible of embodiment in various other forms all 105 coming within the scope of the claims which follow.

I claim:

1. In a cash register, the combination with a group of keys, a series of key stops adapted to prevent the depression of more than one key in the group, each key stop being formed with a T-shaped end, supporting means upon which a portion of said T-shaped ends is adapted to rest, thereby permitting free suspension of said key stops. 100
2. In a cash register, the combination with a group of keys, a series of key stops adapted to prevent the depression of more than one key in the group, each key stop being formed with a T-shaped supporting end, a channel bar member secured to the machine and extending across said supporting ends, and slots formed in the member and adapted to receive the stems of the T-shaped ends of the key stops. 110
3. In a cash register, the combination with a group of keys, a series of key stops adapted to prevent the depression of more than one key in the group, each key stop being formed with a reduced portion and an enlarged end, and a plate provided with depressions and slots, said depressions in the plate supporting the enlarged ends and said slots receiving the reduced portions of the key stops. 115
4. In a cash register, the combination with a group of keys, a series of key stops adapted to prevent the depression of more than one key in the group, each key stop being formed with a reduced portion and an enlarged end, a plate provided with a series of embossed 120 projections, said projections cooperating with the enlarged end portions of the key stops for supporting the latter.
5. In a cash register, the combination of 125

6. a group of keys, a series of pendant oscillatory key stops arranged in alternation with the ends of the keys to prevent depression of more than a single key, and means for supporting said key stops comprising a slotted channel bar, a portion of the stem of said key stops passing through said slots and each of said key stops being provided with an enlarged portion resting on the bar.
10. 6. In a cash register, a key stop provided with a lower wedge-shaped end and an enlarged upper end, supporting means for said key stop, said key stop being adapted to be oscillated, opposite sides of the enlarged upper end acting alternately as the fulcrum points of the key stop during its oscillation.
15. 7. In a cash register, the combination of a key stop provided with a lower wedge-shaped end and an enlarged upper end, a plurality of key levers adapted to rock said key stop in opposite directions, and means for supporting said key stop on opposite sides at its upper end, the opposite sides of the enlarged end acting alternatively as the fulcrum points of the key stop during its rocking by the keys.
20. 8. In a machine of the class described, a single key pendant provided with a T-shaped upper supporting end, and a supporting member therefor comprising a plate having a channel formed therein, and a slot cut across said channel, the cross portion of the upper T-shaped end of said pendant being adapted to rest on a shoulder of said channel form and the stem of said end of the pendant being adapted to pass freely through the slot in said plate.
25. 9. In a machine of the class described, a group of operating keys, a plate having guiding means for the keys, a series of pendants for preventing depression of more than one key in a group at one time, said pendants being provided with a T-shaped end and a stem, said plate being formed with two channel portions at its upper end, one for receiving the stems of said pendants and the other for receiving said T-shaped ends.
30. 10. In a machine of the class described, a group of operating keys, a plate formed with guiding means for the keys, a series of pendants for preventing depression of more than one key in a group at one time, a channel formed in said plate provided with a series of vertical slots for receiving a portion of said pendants, a bearing surface integral with each of said pendants adapted to rest upon one of the legs of said channel thereby holding said pendants in operative position.
35. 11. A plate having a series of vertical key-guiding slots, a channel formed at one end thereof having a series of vertical slots for receiving the stems of key stops, a second channel adjacent said first-mentioned channel for receiving the enlarged ends of said key stops.
40. 12. In a machine of the class described, a

group of keys, a plate having a series of vertical slots for the keys, a series of depending key stops each having an enlarged portion at one end thereof resting upon said plate, the other end of said stops being provided with surfaces adapted to be engaged by certain of said keys, said plate constituting the sole support for said key stops.

13. In a machine of the class described a group of operating keys, a plate having guiding means for said keys, a series of key stops for preventing depression of more than one key in said group at one time, bearing surfaces provided on the upper end of said stops engaging a portion of said plate for retaining the stops in cooperative relationship with the keys, and surfaces provided on the depending end of said stops adapted to be engaged by the keys.
